UNITED STATES PATENT OFFICE.

FREDERICK J. CLARK AND WILLIAM H. WYMAN, OF BUFFALO, NEW YORK, ASSIGNEES
TO EASTMAN MACHINE CO., OF BUFFALO, NEW YORK.

CLOTH-CUTTING MACHINE.

1,253,352.

Specification of Letters Patent. Patented Jan. 15, 1918.

Application filed August 7, 1917. Serial No. 184,959.

To all whom it may concern:

Be it known that we, FREDERICK J. CLARK and WILLIAM H. WYMAN, citizens of the United States, residing at Buffalo, in the county of Erie and State of New York, have invented a new and useful Improvement in Cloth-Cutting Machines, of which the following is a specification.

This invention relates more particularly to improvements in portable cloth cutting machines of the kind that are adapted to be moved about by hand on a cutting table and have a knife which is driven by a motor supported by a vertical standard rising from the base of the machine. These machines are usually provided with a presser foot adapted to bear on the cloth in front of the knife for holding the cloth down against the base of the machine, or a knife guard disposed in front of the knife, the presser foot or guard being mounted so as to enable it to be adjusted vertically as may be necessary when cutting lays of cloth or material which vary in height.

The object of the invention is to provide means of simple and practical construction by which the presser foot or knife guard can be quickly and easily adjusted to and positively secured in the desired position, and which necessitates the use of only one hand for this purpose.

In the accompanying drawings:

Figure 1 is a fragmentary side elevation, on a reduced scale, of a cloth cutting machine embodying the invention.

Fig. 2 is a front elevation of the presser foot or guard and its support detached from the machine.

Fig. 3 is a plan view thereof.

Fig. 4 is a sectional plan view, full size, thereof on line 4—4, Fig. 1.

Fig. 5 is a reverse side elevation, full size, showing the securing means for the presser foot or guard in holding position.

Fig. 6 is a similar view showing the released position of the parts.

Figs. 7 and 8 are views similar respectively to Figs. 5 and 6 of a modified construction.

Fig. 9 is a front elevation of a presser foot or guard and its support showing a guard operating and securing device of another modified construction.

Fig. 10 is a fragmentary side elevation thereof on an enlarged scale.

Fig. 11 is a top plan view thereof.

Fig. 12 is a sectional plan view thereof on line 12—12, Fig. 13.

Figs. 13 and 14 are sectional elevations thereof on line 13—13, Fig. 11.

With the exception of the means herein-after described for adjusting and securing the presser foot or guard, the machine may be of any usual or desired construction, an electric cloth cutting machine of well known construction having a vertically reciprocating knife being illustrated in the drawings. A represents the machine base adapted to rest and move on a cutting table beneath the material to be cut; B the vertical standard which rises from the base and supports an electric motor C; D the knife which is driven by the motor and reciprocates in a vertical guide or slot in the front edge of the standard; E the presser foot, and e the presser bar to the lower end of which the presser foot is secured. The presser foot E and bar e being located as usual in front of the knife D, constitute a guard to prevent a person from being cut by the knife.

In the constructions shown, the presser bar is arranged to slide vertically in a guide slot 10 in a support or block 11 which is preferably detachably secured to the frame in any suitable way, as for instance by a latch lever 12 and a headed stud 13 so that the support with the presser bar or guard in place thereon can be readily applied to and removed from the machine. The detachable mounting of the support 11, however, is not a part of this invention and the presser bar or guard can be slidably mounted on the machine in any other suitable way. 14 represents a stationary locking bar or member which is fixed to the support 11 and extends substantially parallel with the presser bar. As shown this bar is secured on the support 11 at one side of the guide slot 10 and overlaps the presser bar so that it serves to retain the presser bar in its guide slot.

An adjusting handle and securing device projects from the presser bar or guard and cooperates with the locking bar for holding the presser foot or guard in adjusted positions. In the construction shown in Figs. 1 to 6, this device consists of an arm 15 which is fixedly secured to the presser bar and extends forwardly therefrom at one side of the locking bar, a lever 16 which is

fulcrumed or movably connected to the arm 15 and has an angular slot or opening 17 through which the locking bar passes, and a spring 18 which normally holds the lever 16 in a position such as to cause the locking bar 14 to bind in the slot 17 of the lever, as shown in Fig. 5. The outer end of the lever is preferably formed with a flat loop or thumb piece 16^a for the engagement of the thumb. As shown, the arm 15, which is curved, passes through a slot 19 in the lever 16, the lever bears on a cross fulcrum pin 20 passing through the arm 15, and the spring 18 consists of a coiled wire having one end secured to the arm 15 and the other end bearing against the inner arm of the lever. A notch 21 is shown in the presser bar to afford clearance for the inner end of the lever 16. The upper end of this notch 21 also forms a stop to limit the upward movement of the inner end of the lever 16. The lever and arm 15 form a pinch handle operating and securing device for the presser bar. By grasping the outer ends of the lever and arm 15 between the thumb and fore-finger and pressing the parts toward each other as indicated in Fig. 6 the lever will be released from the locking bar 14 and the presser bar and foot or guard can be moved up or down to any desired position by means of the pinch handle. When the pressure on the lever is released it will be swung by the spring 18 to the position to bind on or grip the locking bar 14 and will hold the presser foot or guard positively and securely from upward movement. The presser foot can, however, be lowered into contact with the material being cut by pressing downwardly directly on the presser bar or foot, the lever 16 in such case yielding and permitting the downward movement of the presser bar. The presser foot can thus be easily shoved downwardly against the material either by direct pressure on the foot or presser bar or by means of the pinch handle, and the presser foot can be readily raised by means of the pinch handle securing device. Only one hand is required in operating the presser foot in either way.

50 The presser foot or guard operating and securing device could be of different construction and operate in a similar manner. A different construction is shown, for example, in Figs. 7 and 8. In this construction, 15^a represents an arm fixed to and extending forwardly from the presser bar *e*. Two levers 16^b and 16^c are fulcrumed on this arm, and are provided at their inner ends with slots 17^a through which the locking bar 14 passes. A coil spring 18^a between the outer ends of the levers normally holds them in an inwardly converging position, as shown in Fig. 7. In this position the levers bind on or grip the holding bar and one lever holds the presser bar from up-

ward movement while the other lever holds the bar from downward movement. By pinching together the outer ends of the levers which constitute flat thumb and finger pieces, the presser bar can be moved either up or down to the desired position, the levers constituting a pinch handle for operating the presser foot or guard. The levers 16^b, 16^c are preferably fulcrumed on the arm 15^a in substantially the manner before described; that is, the arm passes through slots in the levers and the levers bear on cross fulcrum pins 20^a passing through the arm. In this construction the levers positively hold the presser bar from both upward and downward movement and the presser foot can only be moved by means of the pinch handle, but, as in the other construction, the presser foot or guard can be quickly and easily adjusted and secured with one hand.

Another form of presser foot or guard operating and securing device is shown in Figs. 9 to 14 and comprises a relatively fixed part 25 secured to the presser foot bar *e* and having a slotted or guide portion 26 embracing the locking bar 14 to guide the presser foot bar in its movement lengthwise of the locking bar. The fixed part 25 has an inclined face 27 which, with the face 28 of the locking bar, forms a wedge shaped recess into which a part of a movable member 28 of the operating and securing device may be pressed to lock the presser foot bar relatively to the locking bar. In the construction shown the movable member 28 is provided with a bar or bolt 29 which is slidable in a recess or slot 30 which extends inwardly from the inclined face 27 of the fixed part 25. The bolt 29 is provided with a notch or groove 31 through which a pin 32 extends which is arranged in the wedge shaped recess. The movable member is preferably pressed away from the fixed part 25 by means of a spring 33 which tends to force the pin 32 into the wedge shaped recess and to lock the presser foot bar to the locking bar. In order to facilitate the releasing and adjustment of the presser foot bar the fixed part 25 and movable member 28 are provided with finger pieces 34 and 35 respectively so that the presser foot bar can be released by pressing together the finger pieces 34 and 35 which causes the bolt 29 to be moved in a direction (upwardly in the construction shown) to move the pin out of wedging engagement with the presser foot bar and the locking bar and permit adjustment of the presser foot bar.

We claim as our invention:—

1. In a cloth cutting machine, the combination with the cutting knife, and a bar adjustable up and down relative to the knife, of a stationary locking member extending substantially parallel with the direction of

movement of said movable bar, and an adjusting device for said movable bar including a part which moves with said movable bar relative to said stationary member and is 5 movable to and from holding engagement with said stationary member for holding and releasing the movable bar.

2. In a cloth cutting machine, the combination with the cutting knife, and a bar 10 adjustable up and down relative to the knife, of a stationary locking member extending substantially parallel with the direction of movement of said movable bar, and an adjusting device for said movable bar including a part which is mounted on said 15 movable bar and is movable into frictional engagement with said stationary member for holding said movable bar in different adjusted positions.

3. In a cloth cutting machine, the combination with the cutting knife, and a bar adjustable up and down relative to the knife, of a stationary locking member extending substantially parallel with the direction of 20 movement of said movable bar, and a part mounted on said movable bar and movable therewith along said stationary member, said part being movable to a position to grip said stationary member and hold said movable bar in different adjusted positions.

4. In a cloth cutting machine, the combination with the cutting knife, and a bar adjustable up and down relative to the knife, of a stationary locking member extending substantially parallel with the direction of movement of said movable bar, and a pinch 25 handle device mounted on said movable bar and coöoperating with said locking member for holding the movable bar in adjusted positions, said device comprising parts arranged to be grasped and pinched between the thumb and finger for releasing and adjusting said movable bar.

5. In a cloth cutting machine, the combination with the cutting knife, and a bar ad-

justable up and down relative to the knife, of a stationary locking member extending substantially parallel with the direction of movement of said movable bar, an arm fixed to and projecting out from said movable bar, and a device loosely mounted on said arm and movable to and from holding relation to said stationary member.

6. In a cloth cutting machine, the combination with the cutting knife, and a bar adjustable up and down relative to the knife, of a stationary locking member extending substantially parallel with the direction of movement of said movable bar, a pinch handle device mounted on said movable bar 55 and coöoperating with said locking member for holding the movable bar in adjusted positions, said device comprising parts arranged to be grasped and pinched between the thumb and finger for releasing and adjusting said movable bar, and a spring for normally holding said pinch handle device in position to clamp said adjustable bar to 60 said locking member.

7. In a cloth cutting machine, the combination with the cutting knife, and a bar adjustable up and down relative to the knife, of a stationary locking member extending substantially parallel with the direction of movement of said movable bar, an arm fixed 70 to and projecting out from said movable bar, a lever which is mounted on said arm and is movable to and from holding engagement with said locking member, and a spring which normally holds said lever in holding 75 engagement with said locking member to hold said movable bar stationary.

Witness our hands this 3rd day of August 1917.
